(57) **CLAIM**

The ornamental design for a garbage bin with lid, as shown and as described.

DESCRIPTION

FIG. 1 is a perspective view of a garbage bin with lid showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a perspective view of the Lid of the garbage bin with lid of my new design in close condition; and,

FIG. 8 is a partial perspective view of the garbage bin with lid of my new design, illustrating the Lid is in open condition.

The broken lines in the drawings depict portions of the garbage bin with Lid that forms no part of the claimed design.
